DESIGN FOR A TOBACCO PIPE

Kurt F. J. Kirsten, Seattle, Wash.

Application October 2, 1937, Serial No. 71,925

Term of patent 14 years

To all whom it may concern:

Be it known that I, Kurt F. J. Kirsten, a citizen of the United States and a resident of Seattle, in the county of King, State of Washington, have invented a new, original, and ornamental Design for a Tobacco Pipe, of which the following is a specification, reference being had to the accompanying drawing, forming a part thereof.

Figure 1 is a perspective view of a tobacco pipe showing my new design;

Figure 2 is a bottom plan view thereof; and
Figure 3 is a perspective view of the opposite side thereof.

The dominant feature of my design is the fluted stem.

I claim:

The ornamental design for a tobacco pipe, as shown and described.

KURT F. J. KIRSTEN.
